UNITED STATES PATENT OFFICE.

JOHN F. O'CONNOR, OF CHICAGO, ILLINOIS, ASSIGNOR TO WILLIAM H. MINER, OF CHAZY, NEW YORK.

RAILWAY-CAR DRAFT-RIGGING.

1,281,641.

Specification of Letters Patent. Patented Oct. 15, 1918.

Application filed November 23, 1916. Serial No. 132,956.

To all whom it may concern:

Be it known that I, JOHN F. O'CONNOR, a citizen of the United States, residing at Chicago, in the county of Cook and State 5 of Illinois, have invented a certain new and useful Improvement in Railway-Car Draft-Rigging, of which the following is a full, clear, concise, and exact description, reference being had to the accompanying drawings, forming a part of this specification.

My invention relates to improvements in railway car draft rigging.

The object of my invention is to provide stop members for railway car draft rigging 15 that are interchangeable one with the other, and where each of said stop members is reversible end for end and face for face.

In the drawings forming a part of this specification, Figure 1 is a horizontal section 20 illustrating an embodiment of my invention; Fig. 2 is a side elevation of one of the stop members; Fig. 3 is a cross section taken on line 3—3 of Fig. 1; Figs. 4, 5 and 6 illustrate a modification, Fig. 4 being a horizontal section of a modified form of stop member, Fig. 5 a side elevation, and Fig. 6 a cross section taken on line 6—6 of Fig. 5.

Referring to the preferred form of my invention illustrated in Figs. 1, 2 and 3 of the drawings, the numeral 7 indicates draft members or parts of the car underframe to which the draft rigging is applied, 8 a drawbar with a yoke 9 secured thereto. The draft rigging illustrated in the drawings is 35 of the tandem type, and the yoke therefor is provided with a front pocket 10, and a rear pocket 11 with intermediate connecting thimble 12. In each of the pockets of the yoke is mounted a compression resisting member 40 14. The front compression resisting member includes the front follower 15 and the front intermediate follower 16 and the interposed springs 17—17. The rear compression resisting member includes the rear intermediate follower 18, the rear follower 19 and the interposed springs 20. Front and rear tie plates 21 and 22, respectively, suitably secured to the draft members as by the bolts 23—23, are adapted to support the yoke and 45 its contained parts between the draft members. The stop members 24—24 are identical in construction, and we will therefore describe one in detail. Each stop member comprises a main web 25 provided at suitable intervals with upright bends on either

side thereof forming the stop shoulders. The front bend in the position in which the stop member is mounted as shown in Fig. 1, referenced 26, forms the front stop shoulder 27. The rear bend 28 forms the rear stop shoulder 29. The middle bend 30 forms the front intermediate stop shoulder 31 and the rear intermediate stop shoulder 32. Intermediate the front stop and the middle stop is an intermediate bend 33 forming the front 65 limiting stop with its front shoulder 34 and its rear shoulder 35. Intermediate the middle stop and the rear stop the bend 36 forms the rear limiting stop with its front shoulder 37 and its rear shoulder 38. The function 70 of the stops and limiting stops, and the action of the followers in reference thereto, is too well known in this art to need any particular description.

The opposed face of each side casting is 75 formed in the same way as the face just described, having a bend 40 from the main web 25 forming the front stop shoulder 41 arranged opposite the front stop shoulder 26 on the other side of the plate, and the similar bends throughout the length of the plate forming the front limiting stop 42 opposed to the limiting stop 33 on the opposed face, the middle stop 43, the rear limiting stop 44, and the rear stop 45 all opposite the 80 similar stops on the opposite side of the main web 25. The faces of all of said stops are provided with the rivet holes 46 for the passage of means such as the rivets 147 for securing the stop members to the draft members. By reason of the construction described, each of the double stops is hollow, as indicated at the numerals 47—47 in Fig. 1 of the drawings, and within said hollow 90 stops bracing ribs or flanges 48—48 are provided to strengthen said stops. The rivet holes through the stops on one face of the stop member, as for instance those referenced 49 in Fig. 2 of the drawings, are staggered vertically in reference to the rivet holes 100 through the faces of the stops on the opposite side of the casting, as indicated at the numeral 50 in Fig. 2 of the drawing.

In the modified form of my invention shown in Figs. 4, 5 and 6 of the drawings, a 105 stop member is shown having a continuous vertical web 60 with vertical bends therein that extend laterally upon either side of a central vertical web 61. The said vertical bends form stops for the followers upon 110

either side of the casting. On one side of the casting, the front bend 62 forms the front stop shoulder 63, the bend 64 forms the front limiting stop with the shoulders 5 65 and 66, and bend 67 forms the middle stop with the front intermediate stop shoulder 68 and the rear intermediate stop shoulder 69, the bend 70 forms the rear limiting stop with its shoulders 71 and 72, and the bend. 10 73 forms the rear stop with its rear stop shoulder 74. On the opposite face of the casting, the bend 75 forms the rear stop shoulder 76, the bend 77 forms the rear limiting stop with its shoulders 78 and 79, the 15 bend 80 forms the middle stop with its rear intermediate shoulder 81 and its front intermediate shoulder 82, the bend 83 forms the front limiting stop with its shoulders 84 and 85, and the bend 86 forms the front stop 20 with its stop shoulder 87. Upon the side of the casting first described, the ends of the followers are shown in dotted lines, the front follower being referenced 88, the front intermediate follower 89, the rear 25 intermediate follower 90, and the rear follower 91. On the opposite side of the casting the ends of the followers are shown in dotted lines, 191 indicating the rear follower, 92 the rear intermediate follower, 93 the 30 front intermediate follower, and 94 the front follower. The central web 61 of the casting forms the faces 95—95 on one side of the casting adapted to guide the ends of the followers on that side, and forms the faces 35 96—96 upon the opposite side of the casting to form guiding faces for the followers on that side. The bends are provided each with suitable rivet holes 97—97 for the passage 40 of rivets, the faces of the stops upon the side marked A, for instance, being placed against the draft sill and riveted thereto when the side of the stop member marked B is employed to provide the stop shoulders for the followers to abut against; and likewise when the side marked A is employed to 45 provide stop shoulders for the followers to abut against the faces of the stops on the side marked B are placed against the draft member and riveted thereto.

50 It will be noted that in the form of my invention illustrated in Figs. 1 to 3 of the drawings and in the modified forms shown in Figs. 4 to 6 of the drawings, the stop members, or cheek plates or stop castings, as they are frequently denominated in this art, are interchangeable one with the other. They are interchangeable end for end, that is, the front stop when the casting is in one position will upon its being turned end for end serve

as a rear stop, and also the said castings may 60 be used with either side backed against and secured to the draft members.

The advantages of my invention are many: in making repairs, when an extra casting may be placed on either side; in giving durability, where first one side of the casting may be used and then the other, and where they may be turned end for end; the ease of application; the strength of the stop members; and other desirable features which will be 65 apparent to those acquainted with the practical application of the art.

I claim:

1. A stop casting for railway draft riggings, said stop casting having stop shoulders on each side thereof, there being spaces between the stop shoulders to accommodate the ends of the followers, the stop shoulders on one side of the casting being opposite the 75 said spaces on the other side of the casting. 80

2. In a draft rigging, the combination with draft sills, of stop members comprising plates adapted to be secured to draft members, the said plates having stops for the followers to abut against on both sides 85 thereof, the said plates being interchangeable with each other, and each plate being usable with either side innermost.

3. In a draft rigging stop member, a plate having a central web and stop shoulders for 90 followers to abut against extending from both sides of said web.

4. In a stop member for railway car draft rigging, a central web, bends extending from either side of the web, forming stop shoulders for followers to abut against on both 95 sides of said web.

5. In a stop member for railway car draft rigging, a plate having front and rear stop shoulders, the said stop shoulders being arranged on both sides of said plate. 100

6. In a stop member for railway car draft rigging, a plate having oppositely arranged stop shoulders on each side thereof.

7. In a railway car draft rigging, a stop member having front, rear and intermediate stops, a main web having faces for the ends of followers to bear against, the said bearing faces and stops being arranged on both sides of said web. 105

8. In a draft rigging for railway cars, a stop member having a main web and double faced hollow stops extended from both sides of the web.

In witness that I claim the foregoing I 115 have hereunto subscribed my name this 16th day of Nov. 1916.

JOHN F. O'CONNOR.
